United States Patent Office

Des. 179,932
Patented Mar. 26, 1957

179,932

CARTON

Grover C. Currie, Charlotte, N. C., assignor to Dacam Corporation, Charlotte, N. C., a corporation of North Carolina

Application November 1, 1954, Serial No. 32,902

Term of patent 14 years

(Cl. D58—12)

Figure 1 is an isometric view of a carton looking down on the top, showing my new design; and

Figure 2 is an isometric view thereof, looking up from the bottom.

I claim:

The ornamental design for a carton, substantially as shown.
